Attorney

UNITED STATES PATENT OFFICE.

JOHN A. ROELL, OF WEST JACKSON, MISSISSIPPI.

RAILROAD-CAR-DOOR SEAL.

Application filed February 12, 1923. Serial No. 618,653.

To all whom it may concern:

Be it known that I, JOHN A. ROELL, a citizen of the United States, residing at West Jackson, in the county of Hinds and State of Mississippi, have invented certain new and useful Improvements in Railroad-Car-Door Seals, of which the following is a specification.

This invention relates to improvements in seals particularly well adapted for the effective sealing of railroad car doors and the like.

The primary object of this invention is the provision of a car seal which is relatively simple in construction, and which may be quickly and conveniently placed in sealing position upon a car, as to prevent any unauthorized opening of the car, without mutilation or destruction of the seal.

A further object of this invention is the provision of a fool proof car door seal, embodying a securing arrangement which will effectively maintain a car door or other device in closed sealed manner, until the seal is broken; the improved seal embodying means to determine the individual by whom, or location at which the sealing operation was effected.

A further object of this invention is the provision of a car seal which may be stamped of sheet material, such as tin, and embodying an arrangement of parts which may be conveniently brought into sealing relation.

Other objects and advantages of this invention will be apparent during the course of the following detailed description.

In the accompanying drawing, forming a part of this specification, and wherein similar reference characters designate corresponding parts throughout the several views,

Figure 1 is a perspective view of the preferred form of improved car seal.

Figure 2 is a fragmentary longitudinal cross sectional view, taken through the improved car seal, showing the same in sealed relation.

Figure 3 is a transverse cross sectional view, taken substantially on the line 3—3 of Figure 2.

Figure 4 is a cross sectional view, taken substantially on the line 4—4 of Figure 2.

Figure 5 is a perspective view of a barb

or locking tongue embodied in this invention.

Figure 6 is a plan view of the sealing end of the improved car seal.

Figure 7 is a fragmentary longitudinal cross sectional view, taken through a modified form of improved car seal, which includes certain novel features also embodied in the preferred form of car seal.

Figure 8 is a developed plan view of the main part of the modified car seal.

Figure 9 is an enlarged perspective view of a seamless guard sleeve, used as a part of the modified car seal.

In the drawing, wherein for the purpose of illustration are shown preferred and modified forms of this invention, the letter A generally designates the improved or preferred form of car seal, while the letter B designates the improved modified form of seal.

Referring to the preferred type of car seal, the same is preferably constructed of good grade sheet material, such as tin, and is preferably of one piece construction. It comprises a body, base, or main portion 15, from one end of which the elongated strap or shackle portion 16 extends; said strap or shackle portion 16 being preferably of a uniform width, and having a substantially polygonal shaped opening 17 at the free end thereof. On the opposite marginal edge or end of the main or base portion 15, the flap portion 18 is provided, which is substantially of the same width as the shackle or strap portion 16, and upon which flap portion 18, the novel locking barb 20 is provided.

At the opposite end of the flap portion 18, the guard flap or tongue 21 is provided, which is of substantially the same width and length as the flap portion 18, and adapted for cooperative protective use upon the improved seal, as will be subsequently described. Guard wings 22 and 23 are provided at the sides of the main body 15 of the improved seal A, extending longitudinally thereof, and which in width are substantially equal to the width of the base portion 15, and in fact, may be of greater width.

The locking clip or barb 20 is of novel construction and is struck from the material of the flap portion 18, so that the free end

thereof is tapered or rounded and extends toward the connection of the flap portion 18 with the main body or base portion 15. The material at the bight or connecting portion of the barb 20, at each side thereof, is removed, as indicated by numeral 25, and the material at the apex of the locking tongue or barb 20 is also removed, as indicated by numeral 26, whereby movement of 5 the locking clip or barb will be unobstructed as to permit the free interlocking of the shackle end with the barb, as will be subsequently described. Intermediate its ends, the barb 20 has the material thereof out- 10 struck, to provide a retaining lug 28, extending substantially outwardly at right angles to the plane defined by said barb, and which cooperates with the shackle or strap 16 in effecting a sealing operation.

15 20 Referring to the assembling operation of the improved car seal A, the flap portion 18 is bent upon the body or base plate 15, substantially as is illustrated in Figure 1 of the drawing, and it is to be noted that the barb 20 is bent downwardly slightly from the plane of its flap 18 as to enter a pocket 30 provided by a depressed portion 31 in the main portion 15. The guard wings 22 and 23 are next overlapped with respect to each other upon 25 30 the flap portion 18, and the guard tongue 21 is next doubled rearwardly and exteriorly of the uppermost guard wing 23, so that the free end of the attaching tongue 21 is disposed adjacent the juncture of the attaching flap with the body 15. It is preferred that the base 15, flap 18, guard wings 22 and 23, and the guard tongue 21 are all transversely welded or riveted adjacent the end of the improved car seal A, so that said parts 35 40 of the car seal provide an attaching or locking head to seal the free end portion of the shackle 16 therein. It will be noted that certain apertures 35 are provided in the portions 15, 18, 22, 23 and 21 of the improved 45 50 car seal, which are disposed in aligning relation in the assembled position of the car seal, and adapted to receive a rivet element 36, upon the heads of which rivet a monogram 37 or other indicia may be provided, representative of the person having charge 55 60 of car sealing operations or of the particular locality from which the sealed cars are shipped. In lieu of the rivet 36, the portions above mentioned may be electrically 65 70 welded to provide a permanent seal at this point. When thus sealed, passageway 39 is provided, intermediate the flap portion 18 and the bottom portion 15 of the seal A, within which the free end of the car shackle 75 80 85 90 95 100 105 110 115 120 125 130 135 140 145 150 155 160 165 170 175 180 185 190 195 198 200 205 210 215 220 225 230 235 240 245 250 255 260 265 270 275 280 285 290 295 298 300 305 310 315 320 325 330 335 340 345 350 355 360 365 370 375 380 385 390 395 398 400 405 410 415 420 425 430 435 440 445 450 455 460 465 470 475 480 485 490 495 498 500 505 510 515 520 525 530 535 540 545 550 555 560 565 570 575 580 585 590 595 598 600 605 610 615 620 625 630 635 640 645 650 655 660 665 670 675 680 685 690 695 698 700 705 710 715 720 725 730 735 740 745 750 755 760 765 770 775 780 785 790 795 798 800 805 810 815 820 825 830 835 840 845 850 855 860 865 870 875 880 885 890 895 898 900 905 910 915 920 925 930 935 940 945 950 955 960 965 970 975 980 985 990 995 998 1000

locking barb 20, the latter will snap through the opening 17, and upon drawing the strap or shackle away from the barb 20, the same will more firmly engage the barb 20, and the retaining lug 28 will be sprung upwardly to engage the free edge 40 of the strap 16, to retain the strap in locked relation with the barb 20, against liability of displacement except by mutilation of the seal.

From this construction of the preferred 75 type of car seal, it will be noted that the attaching or locking head of the same comprises all of the seal except the shackle or strap portion 16, and is protected at all sides, so as to prevent any prying operations, except through mutilation of parts. The attaching or locking head at the entrance of the passageway 39 is doubly protected by the overlapping guard tongue 21, so that it will be impossible to pick the car seal without mutilation.

Referring to the modified form of car seal, the same includes a relatively straight piece of sheet material, such as tin, embodying the base or plate portion 50, which provides the depressed pocket 51 therein, analogous to the pocket 30 above provided for the preferred form of car seal. The strap or shackle 52 is preferably less in width than the portion 50, and extends outwardly from the main portion 50, having an opening 53 at the free end thereof. An intermediate flap portion 54 is provided at the opposite end of the main portion 50, which has a barb or locking tongue 55 struck therein, of preferably the same construction as the locking tongue or barb 20 above described, and which provides a retaining lug 56 outstanding from the plane thereof. The guard or attaching tongue portion 58 extends outwardly from the end of the flap portion 54 opposite the attachment of the latter to the main plate or base portion 50. The portions 50, 54 and 58 are preferably of the same length and width and adapted for cooperative overlapping, as will be subsequently described.

The assembling of the modified car seal B contemplates first, the folding of the flap portion 54 upon the base plate portion 50, so that the barb 55 is swung into the pocket 51. A seamless guard sleeve 60 is provided, open at the ends thereof, and relatively flat, which is adapted for slipping over the overlapped portions 50 and 54, to receive said portions in the pocket or passageway 61 of said seamless sleeve 60, substantially as is illustrated in Figure 7 of the drawing. The guard tongue 58 is then bent exteriorly upon a side of the seamless sleeve 60, and the outer ends of the base 50, flap portion 54, guard sleeve 60, and guard tongue 58 are then permanently sealed, as by a rivet 65 or electric weld. This rivet 65, or electric weld used in lieu thereof, are of course placed remote 130

from the locking barb or tongue 55, as to permit the free end of the shackle or strap 52 to be inserted in the passageway 67 provided at the end of the improved seal device, 5 opposite the riveted or welded end. The free end of the strap, when inserted in the passageway 67, is locked therein, as by springing of the barb 55 and its lug 56 through the opening 53, and interlocking 10 substantially as above described for the preferred embodiment of this invention, and as is clearly illustrated in Figure 7 of the drawing.

Various changes in the shape, size, substitution of equivalents and variations in the 15 form of the improved car seal may be made without departing from the spirit of this invention or the scope of the claims.

I claim:

20 1. A car seal comprising an attaching head having a passageway therein open from an end thereof, said attaching head providing a locking barb extending transversely across said passageway and having 25 a retaining lug extending laterally of the plane of said barb, and a flexible shackle portion connected at one end to said attaching head and having the free end thereof provided with an opening which 30 when the free end is inserted into the passageway of said attaching head will receive said barb therethrough whereby the lug of said barb will be snapped into position to prevent detachment of the free end of the 35 shackle from said barb.

2. A car seal comprising a base portion, a shackle portion extending outwardly from one end of the base portion, a flap portion extending from the opposite end of the base 40 portion adapted for folding upon said base portion whereby the free end of the shackle portion may interlock with said flap portion when so folded, guard means to hold said flap portion in locking relation with 45 the shackle portion, and a guard tongue extending outwardly from said flap portion adapted for exterior attachment upon said guard means.

3. As an article of manufacture, a car 50 seal strip comprising a base portion, a relatively long flexible strap portion extending outwardly from the free end of the base portion, a flap portion extending outwardly from the base portion directly opposite said strap portion, interlocking means on said strap and flap portions, and an attaching tongue extending outwardly from said flap portion opposite to the connection of the latter with the base portion.

60 4. As an article of manufacture, a strip 65 of sheet metal stamped to provide a base portion, a relatively long shackle portion extending outwardly from an end of said base portion having an opening at the free end thereof, a flap portion extending out-

wardly from the opposite end of said base portion having a locking barb struck therefrom, the free end of which locking barb extends toward the juncture of said flap portion with said base portion, so that the same 70 may be received in the opening of said shackle portion, guard flanges extending longitudinally at the sides of said base portion, and a guard tongue member extending outwardly from the flap portion at the end 75 of the said flap portion opposite to its connection with the base portion.

5. A car seal comprising a metal base portion, a flexible strap portion extending outwardly from an end of said base portion 80 having an opening adjacent the free end thereof, a flap portion extending outwardly from the opposite end of said base portion having a locking barb struck therefrom, the free end of which barb extends toward the 85 juncture of said flap portion with the base portion, said flap portion adapted for folding in substantially abutting relation with the base portion, said base portion providing a depressed socket into which said locking barb is normally sprung, guard means sealing the longitudinal sides of the base and flap portions, permanent sealing means connecting said guard means and said base and flap portions at the end of the car seal 90 opposite said strap portion, said strap portion adapted to have the free end thereof inserted intermediate the flap and base portions, whereby the barb of said flap portion may engage through the opening of said 100 strap portion to prevent detachment of the latter.

6. A car seal comprising a base portion having a depression providing a pocket therein, a relatively long flexible strap section extending outwardly from one end of the base portion having an opening adjacent the free end thereof, a flap portion extending outwardly from the opposite end of the base portion and providing a locking barb, the free end of which extends toward the juncture of the flap portion with the base portion, said flap portion adapted for 105 folding in overlapped relation upon the base portion whereby the locking barb is normally sprung into the pocket of the depression provided in the base portion, side guard wings provided laterally on the base portion adapted for relative overlapping upon the flap portion, whereby a passageway is provided intermediate the flap portion and the base portion the entrance to which is at the point of juncture of the strap portion with the base portion, a guard tongue at the end of said flap portion opposite to the connection of the latter with the base portion adapted for overlapping exteriorly upon the side guard wings, and means 115 permanently sealing the free end of the guard tongue and said guard wings to said 120 base portion.

flap and base portion adjacent the juncture of the flap and base portions, said locking barb providing a retaining lug extending laterally thereof, whereby when the free end 5 of the strap is inserted into the car seal intermediate the flap portion and the base portion the locking barb may swing into the

opening at the free end of said strap and said locking lug of the barb engage the free edge of the strap to prevent disconnection 10 of the strap from the locking barb except by mutilation of the car seal.

JOHN A. ROELL.
